Specification for Design.

Patented Jan. 11, 1916.

Application filed November 6, 1915. Serial No. 60,148. Term of patent 3½ years.

To all whom it may concern:

Be it known that I, ALBERT E. NEWTON, a citizen of the United States, residing at Pawtucket, in the county of Providence and State of Rhode Island, have invented a certain new, original, and ornamental Design for a Lace Fabric, of which the following is a specification.

In the accompanying drawing which forms a part of this specification, the figure is a front elevation of a lace fabric embodying my new design.

I claim:

The ornamental design for a lace fabric, as shown.

ALBERT E. NEWTON.
